A. D. BAILEY.

LIFE PRESERVER.

APPLICATION FILED JAN. 9, 1919.

1,313,936.

Patented Aug. 26, 1919.

By *Ama Deane Bailey*
David Davis Attorney

UNITED STATES PATENT OFFICE.

ANNA DEANE BAILEY, OF NEW YORK, N. Y., ASSIGNOR, BY DIRECT AND MESNE ASSIGNMENTS, TO THE G. H. MASTEN CO., INC., OF NEW YORK, N. Y., A CORPORATION OF NEW YORK.

LIFE-PRESERVER.

1,313,936.

Specification of Letters Patent. Patented Aug. 26, 1919.

Application filed January 9, 1919. Serial No. 270,376.

To all whom it may concern:

Be it known that I, ANNA DEANE BAILEY, a citizen of the United States, and resident of the borough of Manhattan, city, county, 5 and State of New York, have invented certain new and useful Improvements in Life-Preservers, of which the following is a specification.

The main object of this invention is to 10 provide a jacket form of life preserver which is reversible, that is to say, which may be secured to the wearer with either side out, which may be secured and adjusted or contracted to fit the body of the wearer conveniently and quickly, and to provide such 15 a life preserver with a reversible hood or head-protecting part.

There are other important objects and 20 advantages of the invention which will appear hereinafter.

In the drawing, Figure 1 is a view illustrating the use of the device;

Fig. 2 a rear view of the life preserver;

Fig. 3 a front view thereof; and

25 Fig. 4 a longitudinal, vertical sectional view.

Referring to the various parts by numerals, 1 designates the back section or part, and 2 and 3 the front sections, which are 30 connected to the edges of the back section and complete the jacket part of the life preserver. The front and back sections are connected by flexible shoulder portions 4, and arm holes 5, are provided.

35 Extending horizontally through the front and back sections are tubular parts or passageways 6, to receive the securing and contracting tapes 7, which extend horizontally around the neck opening. Around the neck opening at the top of the shoulder portions is 40 formed a tubular passage 8, through which a neck-securing and contracting tape 9, passes. Around the neck opening is secured a collar part 10, which is preferably stuffed 45 with soft, buoyant material, such as kapok 11. Secured to the collar part, near the front edges thereof, are tying strings 12, said strings being provided with knots 13, at their ends and passing through apertures 50 14, in the collar part, so that they are slid-

able therethrough and may be conveniently tied, as indicated in Fig. 1, when either side of the collar is outermost.

Secured to the upper edge of the collar part is a hood 15, said hood extending over 55 the head of the wearer, as indicated clearly in Fig. 1 of the drawings. This hood is so constructed that it may be reversed with the jacket. The hood is preferably stuffed with buoyant and protecting material, as indicated at 16 in Fig. 4, to serve as a protection for the head of the wearer. The collar part is preferably formed with ear openings 17, which are preferably placed so as to be adjacent the ears of the wearer when the jacket 65 is in use.

The back and the front sections are stuffed with buoyant material, preferably kapok. Of course it will be understood that the buoyant material may be cork, granulated 70 or in blocks; or any other suitable buoyant material may be used.

What I claim is:—

1. A reversible jacket life preserver comprising a jacket part having arm holes and 75 shoulder portions, securing tapes connected to said body part, a collar portion connected to the shoulder part and extending around the neck opening, securing tapes connected to said collar part, and a hood connected to 80 the upper edge of the collar part and adapted to extend forwardly over the head of the wearer, said hood being reversible with the jacket.

2. A reversible jacket life preserver comprising a back section and two front sections stuffed with buoyant material and formed with horizontally extending tubular passages, contracting and securing tapes 85 slidably through said passages, the free ends of said tape extending beyond the edges of the front sections, a tubular passage formed around the neck opening, and a freely slidably securing and contracting tape 90 extending through said tubular passage. 95

3. A reversible jacket life preserver comprising a back section and two front sections stuffed with buoyant material and formed with horizontally extending tubular 100 passages, contracting and securing tapes slid-

able freely through said passages, the free ends of said tape extending beyond the edges of the front sections, a tubular passage formed around the neck opening, a freely 5 slidable securing and contracting tape extending through said tubular passage, a collar part connected to the shoulder portions,

and a reversible hood connected to the collar part and adapted to extend upwardly and forwardly over the head of the wearer.

In testimony whereof I hereunto affix my signature.

ANNA DEANE BAILEY.
